CLAIM

The ornamental design for a cooking grill, as shown and described.

DESCRIPTION

FIG. 1 is a perspective view of a cooking grill illustrating my new design.

FIG. 2 is a front elevational view thereof.

FIG. 3 is a rear elevational view thereof.

FIG. 4 is a left side elevational view thereof.

FIG. 5 is a right side elevational thereof.

FIG. 6 is a top plan view thereof; and,

FIG. 7 is a bottom view thereof.

The broken lines are included for the purpose of illustrating portions of the cooking grill that form no part of the claimed design.
